AND C. G. A. ROSEN.
BY Joseph B. Gardner
ATTORNEY.

UNITED STATES PATENT OFFICE.

HARRY J. CUNNINGHAM AND CARL G. A. ROSEN, OF SAN FRANCISCO, CALIFORNIA, AS-SIGNORS TO TUNG FOON COMPANY, OF SAN FRANCISCO, CALIFORNIA, A COPARTNERSHIP COMPOSED OF HARRY J. CUNNINGHAM, CARL G. A. ROSEN, AND JOHN J. O'DONNELL.

COUNTERSET.

Application filed October 22, 1923. Serial No. 670,010.

To all whom it may concern:

Be it known that we, HARRY J. CUNNINGHAM and CARL G. A. ROSEN, citizens of the United States, and residents of the city 5 and county of San Francisco, State of California, have invented a new and useful Counterset, of which the following is a specification.

Our invention relates to a counter set particularly adapted for use in connection with 10 playing card games and Chinese games; such as, "Mah Jong," "Mah Chuck," "Woo," etc.

One object of the invention is to provide a 15 counter set of the character described in which the individual units or racks have the same elements and are adapted for use in the same manner as the ordinary racks, but can be fitted together when not in use 20 to collectively occupy a minimum space.

Another object of the invention is to provide a counter set which is extremely attractive in appearance yet can be manufactured at a low cost.

25 The invention possesses other objects and features of advantage, some of which, with the foregoing, will be set forth in the following description of the preferred form of our invention which is illustrated in the 30 drawings accompanying and forming part of the specification. It is to be understood that we do not limit ourselves to the showing made in the said drawings and description, as we may adopt variations of the 35 preferred form within the scope of our invention as set forth in the claims.

Referring to said drawings:

Figures 1 and 2 are perspective views of 40 a pair of the racks of the set.

Figure 3 is a section view of a pair of racks fitted together.

Figure 4 is a perspective view showing all the racks of the set fitted together.

The game of "Mah Jong," herein referred 45 to as one of the games with which the counter sets may be used, is played with sets of tiles having thereon characters denoting the suits, and also having numerals from 1 to 9. The game is played by the 50 players matching up the various tiles by suits until one of the players has matched all of the tiles in his hand, when he will "Mah Jong." The other players then pay

the winner suitable amounts in counters, the values of which are determined by the rules 55 of the game.

The racks usually used in counter sets of the character described consist of a row of pegs or pins on an elongated base and adapted to receive perforated chips or coins, 60 the different pegs being adapted to receive coins of different value so as to permit the ready counting and paying of the coins. This form of counter set, while efficient in 65 operation, makes a cumbersome collection of the racks when gathered together for convenience in carrying, storing, etc. In accordance, however, with our invention, although the racks are adapted to be used in the usual manner, when not in use they 70 may be fitted together with such compactness that the entire set of racks will occupy 75 a space practically no larger than the space required by a single rack. Furthermore, the foregoing feature has been accomplished 80 without detracting from the appearance of the racks, in fact, the racks as designed in accordance with our invention are more pleasing in appearance than the old type.

Briefly expressed the counter set as here 85 shown comprises two pairs of racks having their bases from which extend the coin-receiving pegs and which are formed with a concave bottom and convex top to allow the nesting of the bases. The pegs on one 90 of the racks of each pair are formed hollow and large enough to fit over the other pegs; in this manner when the bases of a pair of racks are nested, the pegs of one rack may lie within the pegs of the other. Four 95 pegs are provided on each base, and are positioned thereon to define the corner portions of a square. The bases are also provided with perforations corresponding in 100 number to the pegs and positioned between and in the same relation as the pegs. This arrangement of the perforations allows the pegs of one pair of racks to extend through the bases of the other pair, and thus permitting the complete nesting of all the racks.

A detailed description follows:

As illustrated in the drawings, the counter set includes four racks 6, 7, 8 and 9 which for convenience in the present description will be grouped in pairs 10 and 105 11. Each rack comprises a base 12 prefer-

ably of thin material and formed to define a concave bottom 13 and a convex top 14 of substantially the same shape, thus enabling the bases to be nested.

5. Four pegs or pins for receiving perforated chips or coins 15 are provided on each base. On one of the racks 6 and 8 of each pair, the pegs 16 are formed hollow and capable of fitting over the pegs 17 of the other racks. In this manner when the base of the first mentioned racks is nested in the base of the second, the pegs 17 will extend into the pegs 16.

10. The pegs as previously stated are positioned on the base so as to define the corner portions of a square, the spacing of the pegs being such as to readily permit the coins to be placed on all of the pegs. Formed in the bases are openings 18 which are arranged 15 in staggered relation to the pegs but spaced similarly thereto. The openings in each pair of racks are aligned when the pegs 17 are fitted into the pegs 16; and furthermore the openings are large enough to accommodate 20 the pegs 16. In this manner either pair of racks may be nested in the other by allowing the pegs of one pair to be passed through the openings of the other pair, as clearly illustrated in Figure 4. With the 25 racks thus fitted together, the pegs extending through the openings will lie between the other pegs, however, sufficient distance remains between the latter pegs to permit the coins to be stored thereon when the device is not in use. It will now be evident 30 that the counter set of our invention requires a minimum space and as a result can be readily carried with the game apparatus without any difficulty.

35. 40. The bases are preferably provided with octagonal sides 21, thus giving the racks an extremely attractive appearance, and at the same time permitting a uniform construction of the racks without impairing their 45 ability to properly nest when the pegs of one pair of racks are not aligned with the pegs of the other pair.

Another feature of our set is the provision 50 of a hump or shoulder 22 at the base of the pegs. This facilitates the removal of the lowest coin on the pegs.

We claim:

55. 1. A counter set, comprising a rack provided with a plurality of hollow pins positioned to receive chips of different representations, a second rack adapted to nest in the first and provided with correspondingly po-

sitioned pins arranged to engage in the pins of said first rack when the racks are nested.

2. A counter set, comprising a rack having a base with a concave bottom, a chip receiving tubular pin extending upwardly from and open at said base, a second rack having a base with a convex top of substantially the same form as the bottom of base 60 of the first mentioned rack whereby said second base may nest in the first, and a chip receiving pin on said second base adapted to lie within said first pin when the racks are nested.

70. 3. A counter set comprising a rack having a perforated base and a chip receiving pin extending upwardly therefrom, and a second rack having a base and a chip receiving pin extending upwardly therefrom and arranged to engage in a perforation of said first base when said latter base is superimposed over the second.

75. 4. A counter set comprising a pair of racks having perforated bases and a plurality of chip receiving pins extending upwardly therefrom, the pins of one of said racks being hollow whereby the pins of the other rack may engage therein when the first rack is superimposed on the second, said perforations being aligned when said pins are in engagement, and a second pair of racks adapted to be superimposed on the first pair and provided with pins similar thereto and arranged to engage in said perforations when said first pair of racks is superimposed on the second.

80. 5. A counter set comprising two pairs of racks having octagonal bases formed with a concave bottom and a convex top of substantially the same shape whereby said bases may nest within each other, hollow pins extending upwardly from the bases of one rack of each pair, pins on the other rack of each pair adapted to engage in the first pins 85 when the first racks of each pair are superimposed on the second racks, said bases having perforations arranged to be aligned when the pins of a pair of racks are in engagement, said perforations being positioned 90 on the bases in the same relation as the pins whereby the pins of one pair of racks may engage in the perforations of the other pair of racks.

100. 105. In testimony whereof, we have hereunto set our hands at Oakland, California, this 17th day of October, 1923.

HARRY J. CUNNINGHAM.

CARL G. A. ROSEN.
